US00D674111S

(12) **United States Design Patent**
Whitehead

(10) **Patent No.:** **US D674,111 S**
(45) **Date of Patent:** **** Jan. 8, 2013**

(54) **CONTAINER**

(75) Inventor: **Lance Whitehead**, Swedesboro, NJ (US)

(73) Assignee: **Agilent Technologies, Inc.**, Santa Clara, CA (US)

(**) Term: **14 Years**

(21) Appl. No.: **29/396,370**

(22) Filed: **Jun. 29, 2011**

(51) **LOC (9) Cl.** **24-01**

(52) **U.S. Cl.** **D24/224**

(58) **Field of Classification Search** D24/216-217, D24/219, 222-226, 227, 231, 232; D10/81; D3/203.1-203.8, 202; 435/288.1, 288.3, 435/304.1, 304.3; 422/500, 547, 548, 549, 422/550, 554, 556, 910; D9/414, 425, 432; D7/550.1, 554.1, 554.3, 554.4; 206/557; 229/407; 220/4.21, 608
